UNITED STATES PATENT OFFICE.

LUIGI CESANA, OF ROME, ITALY.

LINOTYPE-MACHINE.

SPECIFICATION forming part of Letters Patent No. 722,284, dated March 10, 1903.

Application filed May 21, 1901. Serial No. 61,212. (No model.)

To all whom it may concern:

Be it known that I, LUIGI CESANA, a subject of the King of Italy, residing at Rome, in the Kingdom of Italy, have invented certain new and useful Improvements in Linotype-Machines, of which the following is a description.

The present invention relates to an automatic feeding device for linotype-machines, whereby a regular and uninterrupted supply of type-metal is fed to the melting-pot in proportion to the amount withdrawn for casting the type. It sometimes happens that the operator of the machine owing to excessive work forgets to add the necessary amount of type-metal to the melting-pot, and consequently the metal in it is excessively overheated, whereby, besides considerable loss of time, imperfect lines and other inconveniences are caused. Even if the attention of the operator is not taken up by his other duties the introduction of metal into the melting-pot at regular time intervals always causes a lowering of the temperature of the molten metal, and consequently the lines and characters sometimes lack precision and clearness.

According to this invention, even in those linotype-machines which produce lines of different thickness and dimensions, the proportion of type-metal entering the melting-pot to that withdrawn from the latter is maintained constant even in cases where the cast lines are of different dimensions from those to be introduced into the melting-pot.

In order that my said invention may be more clearly understood, I will proceed to describe the same with reference to the annexed drawings, wherein—

Figure 1 is a side view of my improved device applied to a linotype-machine, and Fig. 2 is a detail sectional elevation of the means for lengthening and shortening the rod *f*.

To the upper part of the frame or support *a* of the machine is fixed a second support *b*, which in its turn carries a rectangular guiding-channel *c*, the bottom of which is closed up by an endless chain or belt *d*, on which is placed the metal *q* to be fed into the melting-pot *r*. The belt is operated by means of a gear or a toothed wheel *v*, which receives an intermittent movement by means of a spring *g*, actuated rod *f*, and a roller *h*. Said

rod can be lengthened or shortened in order to increase or decrease, as desired, the speed of the endless belt, which can be arranged to travel the distance of one or several teeth each time the cam-lever and an arm *i*, engaging the rod, are raised. The rod *f* is supported in a guide *j* and can be controlled by means of a screw *k*, these parts being carried by a bracket *l*, secured to a support *m* on the frame. The upper end *n* of the rod, which engages the toothed wheel *e*, is pivoted on *o* to the main portion of the rod, so as to be capable of sliding over the backs of the teeth *v* of the toothed wheel *e*, in engagement with which they are held by a spring *p*.

g' indicates a rod, which is slidably mounted in the guide *j*, the lower end of said rod carrying the roller *h*. A coiled spring *g*, mounted on the rod *g'* intermediate the roller and the guide *j*, exerts a stress on the rod to cause it to normally assume a lowered position, as represented in Fig. 2.

The upper end of the rod *g'* carries an arm *A*, in which is mounted a stud or pin *g²*, upon which is mounted the hand-wheel *k* and the toothed wheel *k'*, which is in mesh with the teeth *f'* on the rod *f*. By turning the wheel *k* in the direction of the arrow, Fig. 2, the rod *f* will be elevated, and by turning said wheel *k* in the opposite direction the rod *f* will be lowered. For the purpose of maintaining the rod in its adjusted position a small toothed wheel *B* is mounted on the stud *g²*, with which wheel a pawl *B'* on a support *b²*, carried by the rod *g'*, engages.

The operation of the apparatus is as follows: Each time that the second cam-lever *X* is raised—that is to say, that on account of the rotation of the said cam around the shaft *y*—the arm *i* passes from the position shown in dotted lines to that shown in full lines. It presses upward the roller *h*, mounted on the rod *f*. This rod may be lengthened or shortened, as required, by means of a screw *k*, so as to turn the wheel *e* a distance of one or more teeth *v*, according to the advancing movement determined for the endless chain—that is to say, according to whether it is desired to cause one, two, or more lines to fall into the melting-pot—and in its upward movement it thus turns the wheel *e* for a distance of, say, two teeth in the direction of the arrow. This

movement causes the endless chain *d*, mounted on a drum *x*, which is fixed to or is a part of the wheel *e*, to advance for a certain distance, so as to cause, say, two lines to fall 5 into the melting-pot. With the operation of the machine it is evident that at each revolution of the shaft *y* the endless chain will advance for a distance of two, three, or four teeth, as desired, so as to cause the desired 10 number of lines to fall into the melting-pot. Each time that the arm *i* returns to the position shown in dotted lines the spring *g* causes the rod *b* to descend to its former position. The point *n* is pivoted to the rod *f* at *o*, so that 15 it may slide over the teeth of the wheel *e* in its descent, and a spring *p* causes it to engage with the said teeth in this upward movement.

The metal pieces are supported at the back 20 by a block *s*, secured to a rail by a hook *t*, so that on arriving at the end of the band's upper surface it is prevented from falling down into the melting-pot by means of an abutment *u*, which serves as a catch and which 25 can be provided with an alarm-signal for the purpose of drawing the operator's attention to the fact that the channel requires to be recharged.

It is obvious that when the metal pieces 30 reach the end of the carrying-surface of the band they will slide down, owing to gravity, into the melting-chamber.

Having now fully described my said invention and the manner in which the same is to 35 be operated, I declare that what I claim as my invention, and desire to secure by Letters Patent, is—

1. In linotype-machines, an automatic device for feeding type-metal to the melting-pot 40 comprising an endless carrier, means for imparting an intermittent movement to said carrier, and means for varying the extent of each movement of said carrier.

2. In linotype-machines, an automatic de-

vice for feeding type-metal to the melting-pot, 45 comprising in combination an endless carrier apron or belt, a drum over which said belt passes, a toothed wheel rotatable with the drum, a vertically - movable rod having a jointed section engaging with the toothed 50 wheel, and means for imparting reciprocatory movements to the rod.

3. In linotype-machines an automatic device for feeding type-metal to the melting-pot comprising in combination an endless carrier 55 apron or belt, a drum over which said belt passes, a toothed wheel rotatable with the drum, a vertically - movable rod having a jointed section engaging with the toothed wheel, a second vertically - movable rod, 60 means intermittently acting upon the latter rod to reciprocate it, and means intermediate the two rods whereby reciprocation of the last-mentioned rod will impart reciprocation to the first rod. 65

4. In linotype-machines, an automatic device for feeding type-metal to the melting-pot, comprising in combination an endless carrier apron or belt, a drum over which said belt passes, a toothed wheel rotatable with the 70 drum, a vertically - movable rod having a jointed section engaging with the toothed wheel, said rod being provided with rack-teeth, a second vertically - movable rod, means for intermittently acting upon the latter rod to reciprocate it, a toothed wheel carried by the said second rod and meshing with the teeth of the first rod, a ratchet-wheel on the shaft of the toothed wheel carried by the 75 said second rod and a pawl engaging with the said ratchet-wheel.

In witness whereof I have hereunto set my signature in the presence of two witnesses.

LUIGI CESANA.
